UNITED STATES PATENT OFFICE.

LEOPOLD RUZICKA, OF GENEVA, SWITZERLAND, ASSIGNOR TO M. NAEF & CO., OF GENEVA, SWITZERLAND, A COMPANY OF SWITZERLAND.

PROCESS FOR THE PREPARATION OF MONOCYCLIC KETONES AND THEIR ALKYL DERIVATIVES HAVING MORE THAN NINE RING MEMBERS.

No Drawing. Application filed November 19, 1926, Serial No. 149,538, and in Switzerland December 15, 1925.

In the prior application Serial No. 36,049 filed June 9, 1925, there is described a process of preparing monocyclic ketones having more than nine ring members, which comprises 5 heating a normal straight chain aliphatic dicarboxylic acid salt of the fourth group of the periodic system especially thorium and cerium, said acid having a carbon chain containing more than ten carbon atoms, the carboxylic acid groups being linked to the end carbons thereof.

It has also been discovered that in a general manner for the preparation of monocyclic ketones having more than nine ring members 15 and of their alkyl derivatives, from the dicarboxylic acids having more than ten carbon atoms in a normal chain or from their alkyl derivatives, the metals and the compounds of metals belonging to the rare earths 20 may advantageously be employed.

According to the present invention lanthanum which belongs to the said metals, or its compounds such as for instance lanthanum oxide are employed either alone or mixed with 25 another metal or metal compound belonging to the said group.

It is also advantageous to use a mixture of several metals of the third or fourth group of the periodic system, these mixtures being obtained artificially or otherwise. 30

Mixtures of the above mentioned dicarboxylic acids or their alkyl derivatives, which are prepared from the pure acids or as they

are obtained in certain technical methods or from natural products give, according to the 35 present invention, mixtures of the ketones or their alkyl derivatives, which, in this form, can also be employed in practice.

For obtaining the mentioned monocyclic ketones it is possible to directly heat the acids 40 or the acid anhydrides alone or in presence of metals or metal compounds at a comparatively high temperature, instead of first transforming the corresponding dicarboxylic acids into salts. In this case the use of metals of 45 the rare earths is also advantageous.

The ketones or their alkyl derivatives obtained by the described process can be used as perfumes or as primary materials for the preparation of other technically important 50 compounds.

Example 1.

The lanthanum salt of 3-methyl-tetradecane-1,14-dicarboxylic acid is heated, preferably in a vacuum, to a temperature of 300 to 500 degrees centigrade and the distillate obtained therefrom is worked up by fractional distillation. The fraction distilling at from 100 to 150° C. at a pressure of 0.5 mm. 55 are then treated with semicarbazide or other reagent usually employed for isolating the ketones.

The formation of the 3-methyl-cyclopentadecanone can be represented by the following 60 equation:

The pure 3-methyl-cyclopentadecanone can also be isolated by treating with acids the semicarbazone purified by crystallization in 70 alcohol and melting at about 164° C.

The 3-methyl-cyclopentadecanone boils at 125° C. (at 0.3 mm.) and has a smell like that of natural musk and can therefore be used as a perfume as well as a primary material for 75 preparing other interesting technical compounds.

Example 2.

3-methyl-tetradecane-1,14-dicarboxylic acid 80 is heated up to above 300 to 500 degrees centigrade and towards the end of the reac-

tion preferably in a vacuum with lanthanum hydroxide in a quantity which does not suffice for completely converting the acid into the normal salt. The product obtained is treated according to the method described in Example 1. 85

Example 3.

A mixture of the lanthanum and cerium salts of 4-methyl-tetradecane-1,14-dicarboxylic acid is heated and worked up as described 90 in Example 1. The 4-methyl-cyclopentadecanone obtained boils at about 125° C. (at 0.3 mm.), gives a semicarbazone melting at about 166° C. and has a smell practically corre-

sponding completely to that of natural musk and can therefore be used as perfume and for preparing other interesting technical compounds.

5 *Example 4.*

4-methyl-tetradecane-1.14-dicarboxylic acid is heated at about 300 to 500° C. and towards the end of the reaction preferably in a vacuum, with lanthanum oxide. The product obtained is worked up as described in Example 3.

10 *Example 5.*

15 The lanthanum salt of tetradecane-1.14-dicarboxylic acid is heated and worked up as described in Example 1. The cyclo-pentadecanone is obtained which distills at about 120° C. (at 0.3 mm.) and melts at 63° C.

20 *Example 6.*

Tetradecane-1.14-dicarboxylic acid is heated at about 300 to 500° C., towards the end of the reaction preferably in vacuum, with lanthanumhydroxide. The distillate resulting therefrom is worked up as described in Example 5.

25 *Example 7.*

30 The anhydride of tetradecane-1.14-dicarboxylic acid is heated to about 300 to 500° C. towards the end of the reaction, preferably in a vacuum with lanthanum hydroxide and worked up as described in Example 5.

35 *Example 8.*

35 A lanthanum salt of tetra-1.14-dicarboxylic acid is prepared by partially neutralizing this dicarboxylic acid with sodium hydroxide and precipitating with lanthanum chloride. The resulting lanthanum salt is decomposed by heating and worked up as described in Example 5.

40 *Example 9.*

45 The lanthanum salt of octadecane-1.18-dicarboxylic acid is heated preferably in a vac-

uum to about 300 to 500° C. and the resulting distillate is worked up by fractional distillation. The fraction distilling at from 140 to 180° C. (at 0.3mm) is then treated with semicarbazide or another reagent usually employed for isolating the ketones. The cyclononadecanone in a pure state can in this manner be isolated by treating the semicarbazone purified by crystallization from alcohol and melting at 184° C. This ketone boils 55 at 160° C. (at 0.3 mm.), melts at 72° C. and has a smell which nearly corresponds to that of civetone. It can therefore be used as a perfume and as a primary material for preparing other interesting technical compounds; by oxidizing the cyclononadecanone with chromic acid heptadecane-1.17-dicarboxylic acid is formed.

60 *Example 10.*

65 A mixture of cyclopentadecanone and cyclohexadecanone is obtained by working up according to the method described in Example 1 a mixture of lanthanum and cerium salts of tetradecane-1.14-dicarboxylic and 70 pentadecane-1.15-dicarboxylic acids.

I claim:

1. A process for the preparation of monocyclic ketones having more than nine ring members comprising heating lanthanum salts 75 of polymethylene-dicarboxylic acids, having more than ten carbon atoms in a normal chain, the carboxylic acid groups being linked to the end carbons thereof.

2. A process for the preparation of monocyclic ketones having more than nine ring members comprising heating a mixture of lanthanum and cerium salts of polymethylene dicarboxylic acids having more than ten carbon atoms in a normal chain, the carboxylic acid groups being linked to the end carbons thereof. 85

In testimony whereof I affix my signature.

LEOPOLD RUZICKA.
